[57] CLAIM

The ornamental design for detachable tool and paint caddy for use with a ladder, as shown and described.

DESCRIPTION

FIG. 1 is a rear perspective view of the detachable tool and paint caddy for use with a ladder showing my new design; FIG. 2 is a front elevation thereof; FIG. 3 is a rear elevation thereof; FIG. 4 is a top plan view thereof; FIG. 5 is a bottom plan view thereof; FIG. 6 is a left-hand side elevation thereof; FIG. 7 is a right-hand side elevation thereof; and, FIG. 8 is a rear perspective thereof shown mounted on a ladder.

The broken lines showing a ladder is for illustrative purposes only and forms no part of the claimed design.
